UNITED STATES PATENT OFFICE.

JOHN ARTHUR JONES, OF LOS ANGELES, CALIFORNIA.

COMBINATION LOCK.

Application filed August 6, 1925. Serial No. 48,669.

My invention relates to and has for its purpose the provision of a combination lock which is extremely simple in operation, inexpensive to manufacture, and capable of a relatively large number of combinations possible, its structural simplicity permitting of a wide and general use of the invention, particularly as a substitute for inexpensive key locks.

10 In the accompanying drawings,

Figure 1 is a longitudinal central sectional view of the lock, with portions in elevation, and illustrating the extended position of the locking element with relation to a keeper;

Figure 2 is a vertical sectional view on line 2—2 of Figure 1, illustrating the bolt in extended position;

Figure 3 is a similar view illustrating the bolt in retracted position;

Figure 4 is a perspective view of one of the permutation locking members;

Figure 5 is a similar view of one of the separating members;

25 Figure 6 is a fragmentary perspective view of the operating shaft, illustrating the shoulders.

Referring specifically to the drawings, in which similar reference characters refer to similar parts, my invention, in its present embodiment, comprises a hollow casing 10 in the open end of which is positioned a block 11, formed with a central opening 12 adapted for the reception of a series of permutation members 13 and spacing disks 14, the latter being held in fixed position within the block 11, by means of peripheral lugs 15, which seat in a recess 16 of the block.

30 The spacing disks 14 are interposed between the confronting surfaces of the permutation members 13 and are formed with peripheral slots 17, which are adapted for registration with similar slots 18 formed on the permutation members.

45 A shaft 19 carries a graduated dial 20 and an operating knob 21, and the shaft extends through an opening in the closure 22 and casing 10 and likewise passes through circular openings 23 and 24 of the permutation members 13 and the disks 14. This shaft intermediate its ends is reduced as at 24 to form two oppositely disposed series of shoulders 25, 26 and 27, which progress in step like formation circumferentially of the

shaft in a spiral direction, and is held 55 in position by a nut 28 disposed on the screw threaded end 29 thereof.

The permutation members 13 are formed with lugs 30 which project within the central openings 23 and each of said lugs is 60 adapted to seat upon the shaft shoulders 25 26 and 27 of the series in the order of their assembly upon said shaft 19, when the latter is actuated in either direction to bring the permutation slots 18 in registration with 65 the fixedly disposed slots 17 of the spacing disks 14.

Dial 20 has imprinted thereon a series of consecutively arranged number or letter designations, and in order to provide a given 70 combination, certain of the letters or numbers are associated with a particular shaft shoulder. For example, if the combination is B, R and E, the revolution of the shaft 19 in one direction will bring the first combination designation in registration with a pointer (not illustrated) and will cause the lug 30 of the first permutation member to engage with and seat upon the first shaft shoulder 25 of one series, which action 75 80 brings the slot 18 of the said permutation member into registration with the slot 17 of the first spacing disk 14. Then the shaft is revolved in the opposite direction to center the dial designation R, which causes the lug 30 of the second permutation member to seat upon the shoulder 26 of the opposite series, to bring its slot 18 into register with the slots of the first permutation member 13 and spacing disk 14. The shaft 85 90 is then revolved in a reverse direction to bring the lug 30 of the third permutation member into seating engagement with the shaft shoulder 27 of the opposing series, at which time all of the slots 18 of the permutation members and spacing disks 14 will 95 be in registration.

A bolt 31 is slidably mounted in the opposite end of casing 10, and has one end reduced to form a blade portion 32 adapted 100 for reception within a slot 33 arranged in the inner end of block 11, and which communicates with the central opening 12. The major portion of the bolt proper is provided with a longitudinal bore 34 in which 105 is slidably mounted a latch 35 adapted for engagement with a closure hasp or the like. Adjacent its outer end, the bolt is formed

with transverse slots 36 and 37, through which extend the protruding ends of a pin 39 carried by the latch 35. A coil spring 40 encompasses bolt 31 having one end abutting the inner end of block 11, while the opposite end engages the ends of said pin 39, whereby the said bolt is normally tensioned in a direction outwardly from the block, so that the latch 35 is normally projected outwardly through an opening in the casing to operative or locking position.

The bolt may be retracted, when the spacing disk and permutation slots 17 and 18 are in registration with slot 33 of the block 11, by means of a head 41 mounted upon a pin 41' seated in the bolt 31. The pin 41' is operable in the registering slots 42 and 43 of the casing and closure 22, respectively.

When the dial 20 has been moved to center the prescribed combination designations, the permutation member slots 18 are successively brought into registration with the spacing disk slots 17 and the slot 33 of the block 11, so that the blade portion 32 of the bolt may be moved into the slots 17 and 18, to retract the bolt and latch 35.

If the lock is attached to a door, the bolt may be retracted from the inside by pressing the exposed end of latch 35 inwardly until free of the flange 44 which it normally engages.

It is obvious that any number of permutation members may be added to increase the number of operations necessary to open the lock, and a greater number of progressively disposed shoulders may be provided upon the operating shaft.

Although I have herein shown and described only one form of combination lock embodying my invention, it is to be understood that various changes and modifications may be made therein without departing the spirit of the invention and the spirit and scope of the appended claims.

45 I claim as my invention:

1. In a combination lock, the combination with a casing, of a shaft operable in said casing and having a dial provided with character designations and an operating knob, a series of permutation members mounted on said shaft, a block in said casing adapted for the reception of the permutation members, said block formed with a slot, a bolt operable in said casing and being held in locked position by said permutation members, a spring normally tensioning said bolt into locked position, spacing disks fixedly disposed between said permutation members and having slots provided thereon, lugs on said permutation members, radially disposed shoulders formed on said shaft, said permutation members and spacing disks having circumferentially disposed slots, certain of the dial character designations indicating the position of the permuta-

tation member lugs relative to certain of the shaft shoulders upon which the said lugs will seat, when the shaft is revolved, to bring the permutation member and spacing disk slots into registration with the block slot, so that the bolt may be adjusted to non-locked position.

2. A combination lock, the combination with a casing, of a shaft operable in said casing and having a dial provided with character designations and an operating knob, a series of permutation members mounted on said shaft, a block disposed in said casing adapted for the reception of said permutation members and provided with a slot, a bolt operable in said casing and having normal engagement with said permutation members, a spring normally holding said bolt in locking position with said members, spacing disks fixedly disposed between said permutation members, lugs arranged on said permutation members, radially disposed shoulders formed on said shaft, said permutation members and spacing disks provided with circumferential slots, certain of the dial character designations indicating the successive lugs on said permutation members to be engaged by the shaft shoulders, when the shaft is actuated to bring the permutation and spacing member slots into registration, and a member for retracting said bolt into said slots.

3. A combination lock, the combination with a casing, a block disposed within said casing and having a slot formed therein, a shaft extending through said casing, a series of permutation members loosely mounted on said shaft and arranged within the block opening, lugs and slots provided on said permutation members, spacing disks interposed between said permutation members and being fixedly held in said block opening, said spacing disks formed with circumferential slots, said shaft having a portion cut away to form a series of oppositely disposed shoulders extending in radial plane co-axially thereof, a bolt operable in said casing, a spring normally urging said bolt to operative position, a dial and operating knob on said shaft, character designations on said dial, the lugs of said permutation members adapted to seat on the successive shaft shoulders when the shaft is revolved, and certain of the character designations indicating a shoulder to be brought into engagement with the permutation member lugs, to cause the permutation slots to register with the other mentioned slots whereby the bolt may be retracted therein.

4. A combination lock, the combination with a casing, of a block disposed within said casing and provided with an opening, and slot, a shaft extending through said casing and having a dial and operating knob disposed thereon, a series of permutation

members mounted on said shaft and operable within the said block opening, spacing disks interposed between said permutation members and fixedly held in the block opening, 5 lugs and slots formed on said permutation members and spacing elements, radially disposed shoulders on said shaft, a bolt operable in said casing, a latch associated with said bolt, a spring surrounding said shaft 10 and tensioning the same to locked position, the shaft adapted for actuation to seat the permutation lugs on the shoulders thereof,

whereby the permutation member slots are brought into registration with the disk and block slots, said bolt having a reduced portion adapted for reception within said slots, certain of said dial characters indicating a shaft shoulder to be engaged by a permutation member lug when the shaft is turned, and an element arranged on said bolt for 15 retracting the same when the reduced portion is in registry with the slots of said permutation member and spacing disks. 20

JOHN ARTHUR JONES.
